UNITED STATES PATENT OFFICE.

JOSEPH PETER SHERIDAN, OF NEW YORK, N. Y.

LUMINOUS LETTER.

1,409,595.

Specification of Letters Patent. Patented Mar. 14, 1922.

Application filed August 18, 1921. Serial No. 493,499.

To all whom it may concern:

Be it known that I, JOSEPH P. SHERIDAN, a citizen of the United States, and a resident of the city of New York, borough of 5 Manhattan, in the county and State of New York, have invented a new and useful Improvement in Luminous Letters, of which the following is a full, clear, and exact description.

- 10 The invention relates to luminous figures visible in the dark.
Prior to this invention certain luminous compounds have been used to paint figures and letters on various backgrounds in order 15 to create signs visible at night, and a general result has been defined that is not visible at any great distance, or a sign the letters of which glow to such an extent that the different lines of the letters seem to merge 20 into one another and are not legible.

The object of this invention is to provide means for making luminous figures that are legible and visible in the dark for some considerable distance.

25 This object is accomplished through defining the desired figure on any background by means of a strip of radium luminous material.

This and other objects of the invention 30 will be more clearly understood from the following detailed description and accompanying drawing.

Figure 1 is a sign showing how the letters are defined by a strip of radium luminous 35 material.

Figure 2 is a cross section along the line 2-2 of Fig. 1.

Referring to the above mentioned figures, a foundation 10 which may consist of a 40 great variety of materials is provided. In this case a plate which is painted black has been selected for the foundation or background. The letters are painted on this background 10 by the use of ordinary white 45 paint or some luminous compound as shown at 11. After the letters have been painted on the sign their edges are defined by means of radium luminous material as shown at 12. In this way we get luminous letters, the 50 margins of which are defined by a strip of

radium luminous material which makes the letter legible.

It is not necessary to first paint the letters on the background, but they may be defined by the use of a strip of radium luminous 55 material. However, good results may be obtained by using a background of any ordinary material and outlining the letters as described in the previous sentence. In case the sign is to indicate a direction and is cut 60 the shape of an arrow, the front edge of the arrow is defined by a strip of radium luminous material.

Another advantage of a sign of this type is that it is cheap to construct; a sign the 65 letters of which are altogether made by means of radium luminous material would be very expensive. Signs constructed by the use of letters defined by a strip of radium luminous material decrease the cost by over 70 one-half.

I would state in conclusion that while the illustrated examples constitute a practical embodiment of my invention, I do not limit myself strictly to the exact details herein 75 illustrated, since manifestly the same can be considerably varied without departing from the spirit of the invention as defined in the appended claims.

Claims—

1. A sign of the class described, comprising a foundation colored to form a suitable background, figures painted on the background with a luminous compound, and a strip of radium luminous paint applied to 85 the figures to define their shape.

2. A luminous figure of the class described, comprising a figure painted on any background by the use of a luminous compound, and a strip of radium luminous material applied to the figure to define the edges of the same. 90

3. A sign of the class described comprising a foundation, a background painted on the foundation by the use of a low grade of 95 radium luminous material, and strips of a higher grade of radium luminous material superimposed on the luminous background to define the figures.

JOSEPH PETER SHERIDAN.
